[57] CLAIM

The ornamental design for a dishwasher basket, substantially as shown and described.

DESCRIPTION

FIG. 1 is a perspective view from the front of a dishwasher basket with the lid open, showing my new design;

FIG. 2 is another perspective view thereof from the rear with the lid closed;

FIG. 3 is a top plan view thereof;

FIG. 4 is a side elevational view thereof; and

FIG. 5 is a sectional view thereof taken along line 5—5 in FIG. 3.
